ABSTRACT: Lead wire extending from motor brush is inserted through coil spring and spring is compressed. Thereafter, terminal is crimped onto end portion of lead wire and holds spring between terminal and brush in a compressed condition. Motor brush with spring and terminal assembled to the lead wire is mounted in housing. The housing is mounted in electric motor in a manner such that brush bears against commutator.

APPARATUS FOR ASSEMBLING A MOTOR BRUSH

This application is a continuation-in-part of application Ser. No. 696,572, filed Jan. 9, 1968 now abandoned.

BACKGROUND OF THE INVENTION

It is common practice in the art of manufacturing electric motors to spring bias the motor brushes against the commutator so that as the brushes are worn away, they will remain in contact with the surface of the commutator. A preferred method of achieving this result is to pass the lead wire extending from the brush through a coil spring, compress the spring, and secure a terminal to the lead wire, the terminal being of a size sufficient to retain the compressed coil spring on the wire and against the brush. The brush, with the terminal and spring on its lead wire, is then positioned in a suitable housing which, in turn, is mounted in the motor in a manner such that the spring always bears against the brush to press the surface of the brush against the surface of the commutator. It has been common practice in the past to perform the operations of assembling the spring to the lead wire and securing the terminal to the end of the lead wire manually. This manual method is relatively slow and expensive for the reason that the technician must hold the spring in a compressed condition while he secures the lead wire to the terminal by soldering or crimping.

The present invention is directed to the achievement of an automatic or semiautomatic method and apparatus for assembling a compressed coil spring to a motor brush lead wire and securing a terminal to the end of the wire. An object of the invention is, therefore, to provide an improved method of assembling a spring to a motor brush lead wire and crimping a terminal onto the end of the wire. A further object is to provide an apparatus which can be operated by an unskilled or semiskilled technician and which will produce a succession of brush-terminal-spring assemblies in which the lead wire lengths will be uniform. A still further object is to provide a method of assembling a compressed coil spring to a lead wire and crimping a terminal onto the lead wire which can be performed with the crimping press or which can be performed automatically.

These and other objects of the invention are achieved in a preferred apparatus embodiment comprising a crimping press having a spring assembling apparatus mounted adjacent thereto. The brush, having a lead wire extending therefrom, is positioned in the assembling apparatus and the spring is located adjacent to the brush. A threading rod is moved relatively through the spring while the lead wire is held by the threading rod thereby to thread the wire through the spring. After threading, a portion of the lead wire is located in the crimping press in a position such that a terminal can be crimped onto it. The spring is compressed during this interval so that after a terminal is crimped onto the wire the terminal retains the compressed coil spring between itself and the surface of the brush.

In the drawings:

FIG. 1 is a plan view showing the spacial relationship of the terminal to the coil spring, the motor brush, the lead wire extending from the motor brush, and the threading rod at the beginning of the operating cycle;

FIGS. 2-5 are views similar to FIG. 1 but showing the positions of the parts at various stages of the operating cycle;

FIG. 6 is a perspective view of a finished assembly comprising a brush, a lead wire extending from the brush, a terminal on the end of the lead wire, and a coil spring compressed between the terminal and the brush;

FIG. 7 is a perspective view with parts broken away showing the manner in which the brush-terminal assembly of FIG. 6 is positioned in a brush holder, it being understood that this holder, in turn, is placed in the electric motor;

FIG. 8 is a front view of a preferred form of the invention showing the end portion of the assembling apparatus and the crimping dies, the crimping anvils, and the feed finger;

FIG. 9 is a plan view of the spring assembling apparatus and showing the lower tooling of the applicator, the parts being shown in this view in the positions they occupy at the beginning of the operating cycle;

FIG. 9A is a fragmentary plan view of the central portion of the assembling apparatus and showing the positions of the parts at the beginning of the wire threading operation;

FIG. 9B is a plan view similar to FIG. 9 but showing the positions of the parts after the spring has been compressed and before crimping of the terminal onto the lead wire;

FIG. 10 is a perspective view of the assembly apparatus;

FIG. 11 is a side view of the rearward side of the assembly apparatus;

FIG. 12 is a front view of the assembly apparatus, FIGS. 11 and 12 being taken along the lines 11-11 and 12-12 of FIG. 9;

FIG. 13 is a view taken along the lines 13-13 of FIG. 9B with the parts broken away in the interest of clarity;

FIG. 13A is a view similar to FIG. 13 but with some parts removed to more clearly show the structure at a base block and wire aligning mechanism;

FIG. 14 is a view taken along the lines 14-14 of FIG. 9;

FIG. 15 is a semischematic perspective view of an apparatus in accordance with an alternative embodiment of the invention, this view showing the positions of the parts at the beginning of the operating cycle;

FIGS. 16 and 17 are views similar to FIG. 15 but showing the positions of the part at successive stages of the operating cycle;

FIG. 18 is a perspective view of a short section of terminal strip, the terminals of which are adapted to be applied to lead wires by the apparatus of FIGS. 24-35;

FIG. 19 is a side view showing the positions of some of the essential parts of the embodiment of FIGS. 24-35 at the beginning of the operating cycle of that embodiment;

FIGS. 20-23 are views similar to FIG. 19 but showing the positions of the parts at successive stages of the operating cycle;

FIGS. 24A and 24B present a side view of a further embodiment of the invention, these two figures being adapted to be positioned against each other to show the entire apparatus;

FIGS. 25A and 25B present a top plan view of the embodiment of FIGS. 24A and 24B;

FIGS. 26A and 26B present a sectional side view of the apparatus of FIGS. 24A and 24B taken along the lines 26-26 of FIGS. 25A and 25B;

FIGS. 27-30 are views similar to FIG. 24A but showing the positions of the parts at successive stages of the operating cycle;

FIGS. 31 and 32 are sectional views taken along the lines 31-31 and 32-32 of FIG. 24A;

FIG. 33 is a sectional view taken along the lines 33-33 of FIG. 30;

FIG. 34 is a view taken along the lines 34-34 of FIG. 24B; and

FIG. 35 is a view taken along the lines 35-35 of FIG. 29.

Referring first to FIG. 6, the disclosed embodiment of the invention is adapted to assemble a coil spring 6 to the lead wire 2 of a motor brush 4, compress the coil spring, and crimp a terminal 8 onto the lead wire. The terminal 8 has a flat platelike section 10, a ferrule portion 20 integral with the plate portion, and a depending flange 12. The platelike section 10 has a central opening 16 through which the wire extends and a slot 18 by means of which the wire is admitted to the opening 16 at the time of assembly. One end of the compressed coil spring bears against the underside of the plate portion 10 of the terminal and the other end bears against the brush 4. The terminals are advantageously provided in the form of a continuous strip as shown in FIG. 1, each terminal being connected to the next adjacent terminal by a connecting slug 19 which is removed at the time of crimping.

The brush-spring-terminal assembly of FIG. 6 is mounted in a cylindrical brush holder 22 (FIG. 7) having a liner 24 extending axially therethrough. The flange portion of the ter-

minal is secured by a screw to the brush holder on its right hand end as viewed in FIG. 7 so that the brush emerges from the left-hand end of the liner. This brush holder is mounted in an electric motor in a manner such that the face of the brush bears against the commutator of the motor and is urged against the surface of the commutator by the compressed coil spring 6.

The essential steps of the method aspect of the invention are illustrated in FIGS. 1-5. At the beginning of the operating cycle, the leading terminal of the strip of terminals will be positioned on a suitable anvil and the brush 4 is located in an assembling fixture (described in detail below) with its lead wire extending transversely of the path of reciprocation of a threading rod 26. The threading rod has a slot 28 in its forward end (FIG. 10) and a pin 30 extends transversely through this slot. The spring 6 is also located in the assembling fixture and in alignment with the rod 26. The rod is moved against the wire so that an intermediate portion of the lead wire 2 is captured in the slot 28 and bent around the pin 30. As the rod moves through the spring 6, the brush and the lead wire are carried relatively towards the crimping zone (which appears at the left in FIG. 2). The spring is moved against an abutment 162 so that it is compressed by the time the rod 26 travels through the spring. After the rod comes to rest and the pin 30 is in alignment with the ferrule portion 20 of the terminal, a wire pulling pin 34 moves downwardly and into a recess 36 on the side of the rod 26. This wire pulling pin 34 moves, in a plane above the plane of the terminal 8, along an arcuate path as illustrated in FIG. 3 until an intermediate portion of the lead wire 2 extends above, and in alignment with, the ferrule portion 20 of the terminal. The wire is then lowered into the ferrule portion 20 of the terminal and the ferrule is crimped onto the portion of the lead wire which extends between the pins 30, 34. The lead wire is thereafter cut by a suitable shearing blade 38, the rod 26 retracts (FIG. 5) and the compressed spring expands so that its ends bear against the terminal and the end of the brush 4. The wire is then slid through the slot 18 in terminal portion 10 and positioned in the opening 16 so that the end of the spring bears against the underside of the plate portion 10 of the terminal.

The essential steps of the method of the invention as described above can be carried out with a relatively simple fixture mounted on the side of a suitable terminal applicator. Alternatively, the invention can be practiced with an automatic or semiautomatic applicator and assembling apparatus of the type which will now be described.

Referring to FIGS. 8 and 9, a preferred apparatus embodiment of the invention comprises an electrical terminal applicator 44 having an assembly apparatus 45 mounted thereon for inserting the lead wire 2 through the coil spring 6, compressing the spring and locating a portion of the lead wire in alignment with an uncrimped terminal on the anvil of the applicator. The assembly apparatus 45 comprises a generally prismatic frame block 48 mounted on a suitable bracket 46 secured to the press platen 42, the frame block extending generally rightwardly from the crimping zone of the applicator as shown in FIG. 9. Frame block 48 has a channel 50 on its upper side, the sides of which are defined by an upstanding wall 106 on the rearward side of frame block 48 and a cover plate 52 secured to the front side of the block.

The previously identified threading rod 26 is disposed in the channel 50 and is secured at its rearward end to a slide block 54 which is disposed at the right hand end, as viewed in FIG. 9, of the channel at the beginning of the operating cycle. A connecting plate 56 is secured to the underside of the slide block 54 and extends laterally through a slot 66 past the rearward side 62 of the frame block. Connecting plate 56 is suitably secured to a drive block 64 (FIG. 11) which has a recess 65 on its rearwardly facing surface. A clamping plate 68 is secured by fasteners in this recess and this clamping plate serves to clamp the end of a clevis 70 to the drive block. Clevis 70 is mounted on the end of a relatively elongated piston rod 72 of a pneumatic piston cylinder, the piston rod 72 and the piston

cylinder extending generally parallel to the rearward side 62 of the frame block 48. Piston-cylinder 74 extends beyond the frame block toward the press frame and is suitably mounted on the press frame by a support bracket, not specifically shown. It will thus be apparent that upon relative movement of the piston rod 72 into the piston cylinder 74, the drive block 64 and the primary slide 54 will be moved towards applicator 44.

The motor brush 4 is mounted in a U-shaped cradle 76 which extends laterally with respect to the frame block. Cradle 76 has an upstanding flange 77 (FIG. 10) at its inner end, this flange having a downwardly extending wire receiving notch 79. The lead wire 2 extending from the brush 4 is positioned in this notch and led across the channel 50 so that it extends transversely with respect to the threading rod 26 as shown in FIG. 9. The wire is held by means of a spring holder which will be described below. The cradle 76 has an integral transversely extending mounting ear 78 by means of which it is secured to a secondary slide member 84 disposed in the channel 50. A latch plate 80 is positioned against the ear 78 and the ear and the latch plate are secured to the side of the secondary slide 84 by suitable fasteners 81. The secondary slide has a longitudinally extending bore through which the threading rod 26 is movable. At the beginning of the cycle, the threading rod is in this bore with its forward end disposed behind the lead wire 2 extending across the channel.

The secondary slide 84 has an integral laterally extending ear 88 at its rearward end. This ear extends through the previously identified slot 66 and is secured to a block 90 disposed adjacent to the rearward surface of the frame block. A pin 92, adjustably positioned in block 90, has an enlarged head 93 which is opposed to the head of a screw 96 threaded through the drive block 64. At the beginning of the operating cycle, the head of the screw 96 will be spaced rearwardly from the head 93 of the pin 92 so that the primary slide 54 will be permitted to move towards the operating zone for a short distance before the screw 96 engages the pin 92 and the secondary slide 84 starts moving towards the crimping zone of the applicator 44. During this interval, the threading rod moves against the wire and forms a bight in the wire as illustrated in FIG. 2.

At the conclusion of the operating cycle, the secondary slide 84 must be returned to its starting position (FIG. 9). This is accomplished by means of a chain 98, the end of which is mounted on a pin 99 in the block 90. This chain extends along the rearward side of the frame block 48, over a sprocket wheel 100, and has its other end fastened to one end of an elongated coil spring 102, see FIG. 11. This coil spring extends towards the press frame and is suitably anchored on the press frame. During movement of the secondary slide towards the operating zone, spring 102 is stretched and returns to its normal position when the secondary slide is retracted from the position of FIG. 9B to the position of FIG. 9. The limit of rearward movement of the secondary slide is determined by a suitable stop shoulder 85 formed on the front plate and adapted to bear against the latching plate 80 as shown in FIG. 9.

As previously noted, the lead wire must be held as shown in FIG. 9 with its axis extending across the channel 50. The wire is held in this position by a retainer spring 108 which is mounted on a fastener 112 adjacent to a notch 104 in the wall 106 of the frame block, see FIG. 11. The spring 108 is bent at its lower end so that the wire can be pulled downwardly into the notch 104 and will be retained in the position shown in FIG. 9 during initial forward movement of the threading rod. While the bight in the wire is being formed, the end portion of the lead wire is pulled from the notch 104 and laid against the side of the threading rod.

At the beginning of the operating cycle, the coil spring 6 is positioned in the channel 50 with its left-hand end as viewed in FIG. 9 located against the surface of a stop plate 162 secured to the left-hand end (as viewed in FIG. 10) of the frame block 48. During the cycle, the spring is compressed and is held in a compressed condition while the terminal is being crimped

onto the wire and while the primary slide 54 returns rearwardly to its starting position. The spring has a tendency to pop out of the channel while it is in a compressed condition and for this reason, it is desirable to provide a holdown plate which bears against the upper side of this spring and holds it in the channel. This holdown plate 114 (FIG. 14) extends through a notch 116 in the sidewall 106 of the frame block 48 and is integral with a downwardly extending flange 118. The flange section 118 extends downwardly in a recess 119 in the rearward side 62 of the frame block. At the lower end, the flange 118 extends forwardly through a notch 122 on the underside of the frame block 48. The flange portion 118 is pivotally mounted at its lower end on a pin 124 extending across notch 122 so that the holdown plate 114 can be moved arcuately upwardly and downwardly. The spring 6 is loaded in the channel 50 when the plate 114 is in its upper position and the spring being held in the channel when the plate 114 is in its lowered position. The lower flange 120 is normally biased downwardly as viewed in FIG. 14 by a spring 126 mounted in a block 128 secured in the recess 122. The holdown device is thus resiliently biased into engagement with the spring 6 as shown in FIGS. 9 and 14. At the beginning of the operating cycle, however, the holdown plate is held in its elevated position by means of a finger 130 on the end of a lever arm 132 (FIGS. 10 and 12), the finger bearing against the underside of the flange portion 120 and holding it in an elevated position against the biasing force of the spring 126. The lever arm 132 is offset intermediate its ends as shown at 134 and is pivoted to the front plate at 136. A rearward extension 138 of the lever arm projects towards the rearward end of the frame block 48 and has a contoured upper edge 146 which is adapted to be engaged by a pin 142 having a roller 144 on its end. The pin 142 is integral with, and extends laterally from, the primary slide member 54 so that it moves forwardly with this primary slide member. The contoured upper edge 146 of the arm portion 138 is such that when the primary slide 54 is in its retracted position, the arm 138 of the lever will be urged downwardly so that the arm 132 and the finger 130 will be urged upwardly and against the underside of the flange 120 whereby the holdown plate 114 is held in its elevated condition. Upon forward movement of the primary slide 54 and the camming pin 142, the lever 132, 138 is swung in a slight counterclockwise arc about its pivotal axis 136 under the influence of a spring 140. One end of this spring is secured to the offset portion 134 of the lever and the other end is suitably anchored to the frame block 48 as shown in FIG. 12. It will be apparent from the appearance of the contoured upper edge 146 of the arm portion 138 that the finger 130 will move downwardly shortly after commencement of movement of the primary slide towards the crimping zone. The spring 6 disposed in the channel 50 will thus be held in the channel prior to compression of the spring by the secondary slide as will be described below.

After the crimping operation has been carried out and while the primary slide 54 is returning to its initial position (FIG. 9) it is desirable to hold the secondary slide 84 in its forward position and hold the spring 6 in a compressed condition as shown in FIG. 9B. It will be remembered that when the secondary slide 84 is in its forward position, the elongated spring 102 tends to return to its normal position and without an auxiliary latching means, which will be described below, the secondary slide 84 will follow the primary slide rearwardly during the return stroke. The secondary slide 84 is latched in its forward position by means of the previously identified latch plate 80 in cooperation with a latching boss 160 on an arm 158 of a lever 154. This lever is pivotally mounted at 156 above the previously identified lever 132, 138 on the cover plate 52 and has an offset portion intermediate its ends which merges with a rearwardly extending arm 148. The underside of this rearwardly extending arm is also contoured as shown at 150 for cooperation with the camming pin 142, 144. A coil spring 152 has one of its ends secured to the end of the arm 148 of lever 154 and is secured at its other end to the frame

block 48. This coil spring normally biases the lever 154 in a clockwise direction so that the latching boss 160 is held in an elevated position. When the camming pin 142 is at the rearward limit of its travel, however, the arm 148 is held upwardly against the biasing force of spring 152 so that the latching boss 160 on the opposite end of the lever is lower with respect to the path of movement of the latching plate 80. It will thus be apparent that when the primary slide 54 moves leftwardly from the position of FIGS. 9 and 10, the pin 142 will move beyond the contoured portion 150 of the edge of arm 148 and the lever 154 will be entirely under the influence of the spring 152. When the secondary slide 84 moves towards the crimping zone, the latching plate 80 moves over the latching boss 160 of the forward arm 158 and the lever is swung through a slight counterclockwise arc during this interval. Subsequently, the spring 152 biases the lever in a clockwise direction so that the latching boss 160 lodges behind the latching plate 80 and holds the secondary slide 84 in its forward position. At the end of the cycle, the pin 142 again engages the contoured portion 150 of the arm 148 and the latching boss 160 is lowered to permit the secondary slide to return to its initial position under the influence of the spring 102.

As previously noted, a plate 162 (FIG. 10) is mounted against the left-hand end of the frame block 48 and functions as a stop at the end of the channel 50 against which the spring 6 is compressed. The plate 162 has a central opening in alignment with the axis of the threading rod 26 to permit passage of the threading rod therethrough and has a pair of opposed arched hoodlike guide members 166 on each side of this opening. The edges of these guides, which define an opening 168, are contoured as indicated at 169 (FIG. 10) to guide the terminal out of the crimping area and to guide the wire through the opening 168 when the completed assembly is removed from the apparatus after return of the secondary slide to its starting position.

When the threading rod 26 moves through the opening in the plate 162 and carries the wire bight towards the crimping zone of the applicator 44, as illustrated in FIGS. 2 and 3, the wire should be lightly clamped against the side of the threading rod. This is accomplished by means of a leaf spring 170 (FIG. 11) which is adapted to resiliently bear against the side of the threading rod and which has an end portion 172 secured to the frame block adjacent to the forward end thereof.

The terminal applicator 44 and the press on which the applicator is mounted can be of conventional design and need not be described in detail for purposes of an understanding of the instant invention. Accordingly, only those structural features of the applicator and the press are disclosed and described below which are necessary for an understanding of the instant invention.

The terminals in strip form are fed over a feed platform 176 (FIG. 8) of the applicator by means of a feed finger 178 actuated by a piston rod 180. The terminal strip is guided by means of a guide 182 (FIG. 9) towards the anvil 174 which supports the leading terminals of the strip during the crimping operation. The leading terminal of the strip is crimped onto the wire 2 by a crimping die 188 and is severed from the next adjacent terminal by a suitable shearing blade 186. The shearing blade and crimping die are mounted on the lower end of the press ram shown at 40.

The previously identified pin 34 (FIGS. 2 and 3) by means of which the wire is aligned with the ferrule forming portion 20 of the terminal is mounted in, and depends downwardly from, an arm 190 of a plate 192. As shown best in FIG. 9, this arm and the plate are located behind the anvil and the terminal to provide clearance for the downward movement of the crimping die. The end of arm 190, in which pin 34 is mounted, is normally located above the left-hand end of the frame block 48. The plate 192 has an integral bushing 200 on its underside and a shaft 196 extends downwardly through this bushing and into a base block 198 mounted on the press platen 42, see FIG. 13. At its lower end, the shaft 196 extends through a bushing 204 in the base block and has a collar 202 mounted

on its end, this collar being disposed in a recess 203 on the underside of the base block. At its upper end, the shaft 196 extends through, and has a bearing in, an arm 201 extending from a raised portion of the base block. A compression spring 206 is interposed between the upper side of the bushing 204 and the underside of the integral bushing 200 so that the plate 192 is permitted to move downwardly against the biasing force of this spring. It will be remembered that such downward movement of the plate and pin 34 takes place after the spring has been compressed and the threading rod reaches the limit of its forward motion as shown in FIGS. 2 and 3. The pin 34 is thus moved downwardly and into the previously identified notch 36 in the end of the threading rod 26 prior to arcuate movement of the pin for the purpose of lining the wire up with the ferrule forming portion of the terminal.

The downward movement of the plate 192 and the pin 34 is brought about by means of a lever 208 (FIG. 13) having a roller 209 on its end which bears against the upper surface of plate 192. Lever 208 is pivotally mounted at 212 on the portion 214 of the base block and intermediate its ends is provided with a transversely extending pin 218. An opening 213 in the lever 208 (see FIG. 9B) through which this pin extends accommodates one end of a spring 216, the lower end of this spring being secured at 222 on the base block 198. The spring 216 thus tends to bias the lever downwardly and to push the plate 192 to its lowered position. At the beginning of the operating cycle, however, the lever 208 is held in its elevated position by means of a lifter arm 224 secured to a bracket 225 extending from the ram 40. This lifter has an elongated slot on its lower end into which the end portion of the pin 218 extends as shown in FIGS. 8, 9, and 13. The base block 198 is provided with a channel-shaped recess to permit downward movement of the lifter. The lower end of this lifter thus holds the lever 208 in its upper position at the beginning of the cycle but upon initial downward movement of the ram 40, the lever 208 is permitted to move downwardly under the influence of spring 216 thereby lowering the plate 192 and the pin 34.

After the plate 192 and the pin 34 have been lowered so that the pin enters the notch 36 in the threading rod 26, the pin is moved along an arcuate path from the position of FIG. 2 to the position of FIG. 3. Such arcuate movement of the pin is brought about by swinging the plate 192 arcuately. The arcuate movement in the plate, in turn, is achieved by means of a bellcrank 228 secured, as by keying to the upper end of a shaft 196 above the arm 201 of the base block. One arm 230 of this bellcrank is provided with a setscrew 234 which bears against an upstanding ear 232 on the edge of the plate 192. The other arm 236 of the bellcrank has a roller 238 on its end which is adapted to be engaged by a camming surface 240 of a camming block 242. This camming block is secured to the ram 40 so that upon downward movement of the ram, as will be apparent from FIG. 8, the bellcrank 228 will be swung in a clockwise direction as viewed in FIG. 13 thereby to move the pin along an arcuate path from the position of FIG. 2 to the position of FIG. 3. The plate 192 is normally biased in a counterclockwise direction by means of a spring 244, one end of which is anchored to a pin 246 extending from the plate 192 and the other end of which is suitably anchored on the press frame. The plate 192 is thus swung in its clockwise arc against the biasing force of this spring so that the spring returns the plate to its starting position at the end of the operating cycle.

As previously noted, it is desirable to sever the projecting portion of the wire which extends beyond the crimp from the terminal. This is accomplished by means of a conventional shearing blade 38 which is also mounted on the lower end of the ram 40 and which severs the wire immediately adjacent to the end of the crimp.

The operating cycle of the apparatus may be initiated by any suitable switch or solenoid valve means. At the beginning of the cycle, compressed air is supplied to the piston cylinder 74 to drive the primary slide 54 towards the crimping zone. The press may be of any suitable type and may be provided with a single revolution clutch to drive it through a single

operating cycle, that is, to drive the ram 40 downwardly and then upwardly. This single revolution clutch, in turn, may be engaged by means of a solenoid controlled by a switch 254 mounted on the end of the bracket 46. The switch 254 has a switch arm 252 on the end of which is a roller 250. This roller is adapted to be engaged by a depending cam 256 of the block 64. As will be apparent from an inspection of FIG. 11, the switch 254 will be closed concomitantly with arrival of the primary slide 54 at the end of its stroke. The ram will thus start to move downwardly substantially simultaneously with the completion of the wire-threading and spring-compressing operation.

The operation of the disclosed embodiment is generally as follows. The operator first places a brush 4 in the cradle 76 and locates the wire in the notch 104 of the wall 106 of frame block 48. He pulls the wire downwardly so it will be retained in this notch by means of the spring 108. He thereafter closes a suitable switch to supply compressed air to the piston cylinder 74 causing the piston rod 72 to move leftwardly and causing the primary slide 54 to move towards the crimping zone. During initial movement of this slide, the threading rod 26 moves through the secondary slide block 84, against the wire, and forms a bight in the wire. This bight is pushed through the spring 6 and through the opening in the end of the plate 162. When the primary slide moves against the secondary slide 84, the secondary slide starts to move with the primary slide so that the cradle 76 and the brush 4 are carried towards the crimping zone. Subsequent to the beginning of movement of the secondary slide, relative movement of the lead wire with respect to the threading rod 26 ceases and the previously formed bight is carried through the spring while it is being pressed and located adjacent to the arm 190 of the plate 192. At the conclusion of movement of the slide members 54, 84, the threading rod will be in the position of FIG. 2 and the ram will be undergoing its downward stroke. Immediately after the start of downward movement of the ram, the pin 34 is lowered under the influence of the spring 216 so that this pin moves into the notch 36 on the side of the threading rod 26. Upon further downward movement of the ram, the pin 34 is caused to move in an arcuate path by the cam 240 which engages the roller 238 on the bellcrank arm 236. After the pin has moved along its arcuate path, the wire will be held by the two pins 34, 30 (the latter pin being in the end of the threading rod 26) and will be in alignment with the ferrule portion of the terminal. The ram then moves to its bottom dead center position, crimps the terminal onto the wire, and the severing member cuts the projecting end of the wire therefrom. Immediately thereafter, the ram starts its upward stroke and the primary slide 54 returns to its initial position. The piston 74 is, for this purpose, a double-acting type and the supply of air to the opposite end of the piston is controlled by a suitable three-way valve or the like. The secondary slide 84 does not follow the primary slide 54 by reason of the fact that the latch 160 bears against the latch plate and holds the secondary slide in its forward position. When the primary slide 54 reaches the limit of its rearward travel, the pin 142 engages the end of the arm 148, swings the lever 154 in a slight counterclockwise arc thereby lowering the latch portion 160 and permitting the secondary slide 84 to return to its starting position under the influence of the spring 102. The compressed spring will tend to pull the wire away from the crimping zone whereby the terminal will be pulled off the anvil and the wire will pass through the opening 164 between the two hoods or flanges 166 on the plate 162. The hold-down plate 114 holds the spring in the channel 50 while it is compressed but releases it at the end of the rearward stroke of the primary slide 54.

While the method aspect of the invention can be carried out with a relatively simple work holder and a manually actuated slide, the disclosed embodiment of the invention presents substantial advantages as regards production and rates. The operations required of the technician are relatively simple; he need only position the spring in the channel 50 and locate the brush in the cradle 76. The wire is then positioned in the notch

in the sidewall 106. The operator then actuates a suitable switch to supply compressed air to the piston cylinder 74. The time required for these operations is substantially no greater than the time required for performing a crimping operation with a conventional crimping press.

FIGS. 15-17 show an alternative embodiment of the invention in which the bight in the wire is pulled through the compressed spring rather than pushed through as in the previously described embodiment. In these figures, the same reference numerals, differentiated by prime marks, are used as in the previously described embodiment where appropriate. Structural features of the embodiment of FIGS. 15-17, which are not present in the previously described embodiment are identified with new reference numerals.

In the embodiment of FIG. 15, the threading rod 26' is reciprocably mounted in a supporting block 276 disposed on the side of the anvil which is opposite to the side on which the frame block 48' is positioned. The threading rod 26' has a recess 277 adjacent to its end which extends inwardly from the side of the rod and towards its leading end. A pair of wire clamping fingers 278 are pivotally mounted on spaced-apart axes 280 on each side of the threading rod, these fingers being received in a recess 282 in the front of the block 276. At their rearward ends, the fingers 278 are resiliently biased apart by a spring 284 so that their forward ends (at right hand ends in FIG. 15) are resiliently biased towards each other. The lower finger 278 has a clamping wheel 288 mounted on its end, the periphery of which is provided with a V-notch. The upper finger is provided with a similar wheel 286 having a bevelled or periphery which conforms to the V-notch of the wheel 288. These peripheries of the two clamping wheels normally nest within each other and, by virtue of the spring 284, a wire held between their peripheries will be lightly clamped.

The slide 54' is mounted directly on the end of a piston rod 258 of a suitable piston-cylinder (not specifically shown) and is contained in the channel 50' of the frame block 48'. The cradle 76' in which the brush is mounted is integral with, and extends laterally from, slide 54' and has a plate 77' on its inner end which is notched at 49' for reception of the lead wire. A platform 264 extends laterally on the opposite side of the slide 54' and has a clamping means on its upper surface comprising wire clamping blocks 266, 268. The block 268 is resiliently biased towards the block 266 so that a wire held between the opposed sides of the block will be lightly clamped. The sidewalls of the frame block 48' on each side of the channel 50' have elongated slots 272 which communicate with the upper side of the block 48' provided with a plate 287 which partially covers the end of the channel 50' and which has a circular opening to permit passage of the threading rod 26'.

The operation of the embodiment of FIGS. 15-17 is as follows. With the parts in the position of FIG. 15, the operator positions a spring 6 in the channel 50' with the end of the spring abutting the plate 287. He then positions a brush in the cradle 76' and locates the lead wire extending from the brush in the clamping means 266, 268 with the axis of the lead wire extending transversely across the channel 50'. He then actuates the piston-cylinder of the piston rod 258 to cause relative movement of the slide 54' towards the plate 287. During such movement of the slide 54', the spring will be compressed, the flange 260 on the leading end of slide 54', and the brush and its lead wire will be carried relatively towards the left-hand end of the frame block until the parts are in the positions of FIG. 16.

Thereafter, the threading rod 26' moves across the upper surface of the anvil, through the opening in the plate 286, through the compressed coil spring, through the opening 262 in flange 260, and past the transversely extending lead wire. The wire will be urged upwardly by the leading end of the threading rod and will then lodge in the slot 277 of the leading end of the threading rod. The threading rod then returns to its starting position and pulls the wire through the spring. When the threading rod passes the fingers 278, the wheels 286, 288 will lightly clamp the wire and locate it with its axis extending

above the ferrule portion of the terminal. The ferrule portion of the terminal is then crimped onto the wire and the excess wire which extends beyond the ferrule is severed as previously described.

FIGS. 24-35 show a further embodiment of the invention which is adapted to crimp a terminal of the type shown in FIG. 18 onto a lead wire 2 extending from a brush 4 and to compress a spring 6 at the time of application of the terminal. The terminal 330 has a U-shaped crimp section 332 which is integral with a continuous carrier strip 328 at one end and which has a neck 334 extending from its other end. The neck is bent downwardly, as viewed in FIG. 18, as shown at 336 and is integral with a plate section 338. A slot 340 in this plate section is in alignment with the crimp section 332 so that a hookup wire or the like 324 can be connected to the lead wire 2 when the terminal is crimped onto both wires, as best shown in FIG. 23.

The principles of operation of the embodiments of FIGS. 24-35 can be understood from FIGS. 19-23 which show some of the essential elements of this further embodiment and the manner in which they cooperate during operation.

The threading rod 298 in this embodiment has an axially extending eye 300 adjacent to its end which opens onto the upper side of the rod at 302 so that the lead wire 2 can be passed through the entrance 302 to the eye and positioned as shown in FIG. 20. The spring 6 is manually positioned on the rod prior to threading of the lead wire through the eye 300 so that at the beginning of the operating cycle, the parts will be in the position of FIG. 20. The brush 4 is held by a brush holder, one end of which comprises a platelike section 308. The portion 308 of the brush holder bears against the left-hand end of the spring, as viewed in FIGS. 20 and 21, during rightward movement of the brush holder to compress the spring against one end 304 of a spring holder 306. The exact structures of the brush holder, the spring holder 306, and the other elements shown fragmentarily in these figures are described in complete detail below.

The brush holder moves upwardly during the initial operating cycle so that the brush is in alignment with the spring immediately before, and during, crimping of the terminal onto the wire. Threading of the wire 2 through the spring is achieved by rightward movement of the rod 298 from the position of FIG. 20 to the position of FIG. 21, the end of this rod being disposed in a passageway in a pilot block 310 after conclusion of its rightward movement. The lead wire is pulled through an opening in the wall 304 of the spring holder, through an opening in a wire retainer 312 and is lightly held in this wire retainer by virtue of its natural tendency to assume an arcuate configuration.

After compression of the spring against the wall 304 of the spring holder, an insulated wire 324 is positioned in a recess 325 in the pilot block 310 so that the stripped end of this wire is directly above the terminal positioned on the anvil 316 and beneath the lead wire 2 extending from the brush 4. The anvil 316, which forms part of the applicator structure, is disposed adjacent to a depressible shearing block 320 having a slot 318 which receives the carrier strip 328. Upon downward movement of the crimping die 322 the terminal supported on the upper surface 314 of the anvil is crimped onto the two wires 324, and 2. Concomitantly, the shearing block 320 is depressed and the crimped terminal is sheared from the carrier strip as illustrated in FIG. 22. After subsequent upward movement of the crimping die, the brush, having the terminal crimped onto its lead wire and having a spring compressed between the terminal and the end of the brush, is ejected from the apparatus as illustrated in FIG. 23.

Referring now to composite FIGS. 24-26, the apparatus 790 in accordance with this embodiment comprises a terminal applicator 292 having a ram housing 293 in which an applicator ram 294 is reciprocably mounted. It will be understood that the ram 294 will be coupled to the ram of a suitable press (not shown) and that the base plate 295 of the apparatus will be mounted on the platen 296 of the press. The base plate has

an enlarged central section 297 on which the applicator is mounted and has relatively narrow aligned arms 299, 301 which extend in opposite directions from the enlarged central section as viewed in FIGS. 24-26. The applicator will conventionally include the strip feeding means for feeding the terminal strip 326 towards the crimping zone to position the leading terminal of the strip on the supporting surface 314 of the anvil 316.

The right-hand end 342 of the previously identified threading rod 298 has a block 344 secured to its end which is received between upstanding ears on the upper end 348 of a mounting pedestal 346, see FIGS. 24B, 26B and 34. This pedestal is provided with laterally extending feet on its lower end which are secured to fasteners 347 to a reciprocable threading rod slide 350. Slide 350 is reciprocably mounted on the upper surface of the base plate arm 299 between suitable guide gibs 354. Slide 350 and the threading rod 298 are reciprocated by a pneumatic piston-cylinder 356 secured by suitable brackets to the front of the apparatus and having a piston rod 358 which extends parallel to the slide and the section 299 of the base plate. The end of this piston rod 358 is provided with a clevis 360 which receives a depending arm 362 of a connecting block 364. Block 364 extends over the upper surface of the slide 350 and is secured thereto by fasteners 366. It will thus be apparent that upon rightward movement of the piston rod 358 from the position shown in FIG. 25B, the threading rod slide and the threading rod will be moved rightwardly as viewed in FIG. 24A and in FIGS. 27-29.

The threading rod is supported intermediate its ends by a pilot block 368 mounted immediately beneath the applicator housing 293 and having a rearwardly extending arm 374 which is secured to the base plate by screws or other fasteners 376. An opening 370 is provided on the upper section of this pilot block and a counterbored bearing is disposed in the left-hand end of this opening a shown at 372, the reduced-diameter section of this bearing being substantially equal to the diameter of the threading rod. The previously identified wire positioner plate 312 is disposed adjacent to, but spaced from the left-hand end of this opening as viewed in FIG. 26A and in a plane beside the plane of the anvil 316 on which the terminal is supported. An oversized opening 380 is provided in positioner plate 312 through which the threading rod extends when the parts are in the position of FIGS. 24A and 27. During retraction of the threading rod, the lead wire from the brush is pulled taut and slips from the eye in its end. The lead wire, being a multistrand relatively soft copper wire, has a natural tendency to curl when it is unsupported so that its end portion will assume a position similar to that shown in FIG. 28 after the threading rod has passed the wire positioner plate and the lead wire will therefore be supported above the crimp portion of the terminal on the anvil. The positioner plate in the disclosed embodiment is secured to the pilot block by means of an integral mounting portion 382 which is secured to the block by suitable screws as shown.

The brush from which the lead wire 2 extends is supported during the operating cycle in a brush holder 384 which is disposed at the beginning of the operating cycle, immediately to the left of the end of the threading rod as viewed in FIG. 24A. This brush holder has top and rear walls and an end wall 308 which was described previously and which bears against one end of the coil spring during compression thereof. The front of the brush holder, that is, the right-hand side as viewed in FIG. 31, is open so that the operator can position the brush in the holder by merely locating it against a supporting plate 400 and against the backwall of the brush holder. This supporting plate is adjustably mounted by means of a depending ear 402 in a recess of a vertical slide member 386 as described below. For a particular size brush, the position of the plate 400 is located such that the brush can be positioned in the holder and lightly held by the frictional engagement of the plate with a side of the brush. The front wall 308 of the holder is divided by a slot so that a wire can be lead through the wall and positioned in the eye of the threading rod.

For reasons which will become apparent as this description proceeds, the brush holder is raised during the initial portion of the operating cycle from the position of FIG. 24A to the position of FIG. 27 and is lowered after a terminal has been crimped onto the wire. Such vertical reciprocation of the brush holder is achieved by means of a depending slide body 386 which is integral with the brush holder and which is contained between a slide body housing comprising two sections 388, 390. These sections surround the slide body and are secured together by suitable screws 391. The slide body housing section 388 has laterally extending ears 392 (see FIG. 26A) by means of which it is secured to a brush holder slide 396 mounted on the upper surface of the base plate section 301 between suitable guide gibs 398. The lower portion of the slide body 386 and the slide body housing extend through an elongated slot 389 in the base plate section 301, this slot permitting rightward movement of the slide body and housing from the position of FIG. 26A to the position of FIG. 28.

The horizontal brush holder slide 396 is moved rightwardly during the operating cycle from the position of FIG. 24A to the position of FIG. 28 by an extensible coupling between this slide and the connecting plate 364 which is secured to the piston rod 358. This extensible coupling comprises a cylinder 416 having a clevis 418 on its end which is secured to an ear 420 on the plate 364. The piston rod 414 of the cylinder 416 is rigidly secured to a connecting rod 412 which extends leftwardly past the brush holder and is secured at its end 410 to a frontwardly extending ear of a plate 406. Plate 406, in turn, is mounted on the upper surface of the horizontal brush holder slide 396 and is secured thereto by fasteners 408. The left-hand end of the cylinder 416 is pressurized by a suitable air-hose 422 however, the right-hand end of this cylinder is not pressurized.

The horizontal brush holder slide 396 is shown in FIG. 26A in the position it occupies at the limit of its leftward travel and this slide moves rightwardly from the position of FIG. 26A until a stopblock 424 secured to its underside by fastener means 426 moves against a fixed stop 428 mounted on the underside of the base plate. The rightward stroke of the horizontal brush holder slide 396 is considerably shorter than the stroke of the piston rod 358 so that this brush holder slide comes to a stop prior to the end of the stroke of the piston rod. It is for this reason that the extensible coupling 414, 416 is provided between the brush holder slide and the connecting plate 364. After the cessation of rightward movement of the brush holder slide, the cylinder 416 continues to move rightwardly but the piston on the end of the piston rod 414 (which is within the cylinder 416) remains stationary and the cylinder 416 and the piston rod 414 therefore assume an extended position with respect to each other. During subsequent initial leftward movement of piston rod 358 (i.e. during initial movement of this piston rod into cylinder 356), the cylinder 416 is moved leftwardly by the connecting plate 364 relative to the piston rod 414. The piston rod 414 and the horizontal brush holder slide 396 remain stationary during this interval until the cylinder 416 and piston rod 414 are fully telescoped together. Thereafter the cylinder 416 and piston rod 414 move leftwardly as a unit and the horizontal brush holder slide 396 is moved leftwardly by the connecting rod 412 which is secured to one end of piston rod 414. Leftward movement of these parts ceases when the piston rod 358 reaches the end of its leftward stroke at which time the brush holder slide will be in the position of FIG. 26A. An immediate return of the horizontal brush holder after the crimping operation has been completed is desirable in order to actuate an ejection mechanism for the brush-spring-terminal assembly which will be described below.

The brush holder is raised during the operating cycle from the position of FIG. 24A to the position of FIG. 27 by the vertical brush holder slide 386 during movement of the horizontal brush holder slide. It should be mentioned that the brush holder is located below the level of the end of the threading rod 298 at the beginning of the operating cycle in order to permit the operator to telescope the spring over the end of the

threading rod as indicated in FIG. 24A. The lowering of the vertical brush holder slide which takes place after the crimping operation has been carried out is also utilized to actuate an ejection mechanism referred to above.

Referring to FIGS. 24A, 26A and 31, the vertical brush holder slide 386 and the brush holder 384 are raised by means of a cam follower 430 mounted on a pin 432 extending from a block 434 secured by fasteners 436 to the lower end of the vertical brush holder slide. The cam follower 430 is received in a generally trapezoidal recess 440 in a fixed camming block 438 secured to the underside of, and depending from, the base plate. The recess 440 has inclined sides 439, 441 and is divided into two sections by an oscillatory divider 442. This divider functions to define separate cam tracks for the follower 430 for its rightward and leftward movement to achieve raising and lowering of the vertical brush holder slide 386 in a manner which will be described below.

The divider has rightwardly and leftwardly extending arms and is mounted intermediate its ends on a pin 444 (FIG. 32) which is integral with, and extends from, a bearing 446 mounted in the camming block. A cylindrical boss 448 is secured to the bearing 446 and the divider 442 by fasteners 447. Boss 448 is disposed against the left-hand side of the camming block as viewed in FIG. 32 and has a pin 450 extending radially from its one side. A spring 452 has one end secured to the pin 450 and has its other end secured to a suitable fixed pin on the press frame so that the bearing 446 and the divider 442 are biased in a counterclockwise direction as viewed in FIG. 26A.

When the divider is in the position of FIGS. 24A and 26A the cam follower 430 will be disposed in a pocket 453 at the lower left-hand end of the trapezoidal recess 440, this pocket being obscured in FIGS. 24A and 26A but being shown in FIGS. 27-29. The divider will thus define an upwardly inclined cam track 454 which merges with a horizontal cam track 456. As the cam follower moves along cam track 456, during rightward movement of the horizontal brush holder slide 396, the cam follower will engage the inclined section 457 of the divider and cause the divider to swing through a slight clockwise arc about its pivotal axis. When the divider is thus shifted about its axis, the horizontal track section 456 is extended as shown at 458 (FIG. 27) and the cam follower is permitted to move along a horizontal path until the stop block 424 on slide 396 moves against the fixed stop block 428. The brush holder is thus raised by virtue of the upwardly inclined cam track section 454 during initial rightward movement of the horizontal slide 396 and then is moved rightwardly to the limit of its stroke in its raised position.

When the horizontal brush holder slide reaches the limit of its rightward stroke, the cam follower 430 will have moved beyond the right-hand end of the divider, as shown in FIGS. 27 and 28, so that the divider, under the influence of the spring 452 will return to its normal position. The divider now defines a return path for the cam follower which provides a downwardly inclined cam track 455 which merges with a horizontal section 443. It follows that during the return movement of the horizontal brush holder slide, the vertical brush holder slide will be lowered during the initial portion of the rearward stroke and will travel rearwardly along a horizontal path after the cam track portion 443 is engaged. At the end of the rearward stroke, the cam follower engages the left-hand end of the divider and swings the left-hand divider arm through a slight clockwise arc against the biasing influence of the spring 452 so that the cam follower can pass the end of the arm and enter the previously identified pocket 453.

The previously described spring holder 306 has a top wall 466 depending sidewalls 468, 470, and a front wall 304 through which the threading rod moves and against which the spring is compressed. The underside and the left-hand end of the spring holder are open although a fixed support plate 488, extending from a bracket 490 secured to the mounting block as shown, supports the forward end of the spring during compression.

Referring now to FIG. 31, an arm 472 is integral with sidewall 470 intermediate the ends thereof and extends rearwardly to a block 480 on the end of a piston rod 482. The arm is pivoted intermediate its ends at 474 between the upstanding ears 476 of a block 492 and is pivotally connected at its left-hand end 478 to the block 480. The piston rod 482 extends from a pneumatic cylinder 484 which is pivotally or otherwise mounted at its lower end and which is supplied with compressed air from a line 486. It will be apparent that upon relative downward movement of the piston rod 482 from the position shown in FIG. 31, the arm 472 will be swung about its pivotal axis 474 through a slight counterclockwise arc thereby raising the spring holder from the position shown in FIG. 31. The spring holder normally occupies the position shown in FIGS. 24A, and 31 and is raised after the crimping operation has been carried out in order to permit removal of the finished brush-spring-terminal assembly.

Referring now to FIGS. 25A and 33, the finished assembly is ejected from the apparatus by means of an ejector plate 494 which extends through a slot in the block 492 and is pivotally mounted therein by means of a pin 496. The end of this plate 498 projects into the path followed by the brush holder during its return stroke, that is during movement of the brush holder from the position shown in FIG. 29 to the position shown in FIG. 30. The inclined leading edge of this plate is adapted to enter an elongated slot in the rearward side of the brush holder so that the plate will push the brush out of the brush holder as indicated in FIG. 30. The portion of the plate 494 which extends rearwardly beyond the surface of the block 492 has a pin 505 therein to which one end a spring 506 is connected, the other end of the spring being secured to a suitable fixed pin 502 in the block 492. The plate 498 is thus biased in a clockwise direction as viewed in FIG. 33 but can be moved counterclockwise on its pivotal axis against the biasing force of the spring. During rightward movement of the brush holder, portions of the brush holder move past this ejector plate and the plate is required to swing through a slight counterclockwise arc to permit passage of the brush holder. During leftward movement of the brush holder, the slot knocks the brush out of the brush holder as indicated in FIG. 33.

The shear 320, which was briefly described above, is contained in a vertical recess in a mounting block 508 and is biased upwardly by means of a spring 506 which extends into a recess in the lower end of the shear. A pin slot connection 510, 511 between the shear block and the housing block maintain the parts in assembled relationship and guide the shearing block along an accurate path during downward movement. The shear is lowered during the crimping operation by means of a boss 512 integral with the shearing block which extends into the path of the crimpler and is engaged by the lower end 514 of the crimpler as indicated in FIG. 35.

It is believed that the operation of the embodiment of FIGS. 24-35 will be apparent from the foregoing description. In general, it is only necessary for the operator to position the spring on the threading rod and position the brush in the brush holder with the lead wire in the eye of the threading rod. Upon actuation of the apparatus, the threading rod is moved rightwardly and the brush holder is moved rightwardly and upwardly until the spring is compressed along the end wall of the spring holder and the lead wire is disposed in the terminal position on the anvil. The operator then positions the additional wire 324 in the recess 325 of the pilot block so that the stripped end is between the lead wire from the brush and the crimp portion of the terminal. The operator then actuates an additional switch to energize the press and move the crimping die downwardly. Such downward movement of the crimping die results in the crimping of the terminal onto the two wires. Upon subsequent return of the parts to their initial positions, the completed assembly is ejected as described above.

The control system for the apparatus may be of any desired type. Advantageously, separate actuating means are provided for the piston-cylinder 356 and for the press to which the applicator ram 294 is connected. Compressed air can be sup-

plied to the piston cylinder 356 by a conventional solenoid actuated valve. If the press is operated by an electric motor, a separate switch should be provided for engaging the motor clutch to drive the press ram and applicator ram downwardly. Such separate controls will have the effect of interrupting the cycle so that the operator can position the additional wire 324 in the recess 325 of the pilot block 310 after the first portion of the cycle has been carried out. Compressed air may be supplied to the piston-cylinder 484 by solenoid valves which may be actuated by the press ram.

While the invention is herein disclosed with reference to the assembly of springs to wires extending from electrical brushes, it will be apparent that the invention is amenable to other uses. Modifications of the invention can be used to compress a spring which is to be held between two platelike members. 15 Devices of this type are useful as mounting means capable of absorbing vibrations.

Changes in construction will occur to those skilled in the art and various apparently different modifications and embodiments may be made without departing from the scope of the invention. The matter set forth in the foregoing description and accompanying drawings is offered by way of illustration only.

We claim:

1. Apparatus for compressing a coil spring and confining said spring between two solid members, said members being connected by a wire or the like attached at each end to one of said members and extending axially through said spring, said apparatus comprising:

applicator means for securing said wire to one of said members,

supporting means for the other one of said members,

threading rod means having a free end, wire-holding means on said free end of said threading rod means, said threading rod means being reciprocable along a predetermined path extending from a first position adjacent to said supporting means to a second position adjacent to said applicator means,

abutment means on said path, said threading rod being movable relatively through said abutment means and said spring, said abutment means being effective to support the one end of said spring which is adjacent to said applicator means, and

means for compressing said spring against said abutment means whereby

upon positioning said wire in said wire-holding means when said threading rod is in said first position, movement of said threading rod relatively through said spring to said second position, compression of said spring against said abutment means, and actuation of said applicator, said wire is threaded through said spring, said spring is compressed, and said one of said members is secured to said wire and holds said spring in a compressed condition against said other one of said members.

2. Apparatus for assembling a compressible spring to a lead

wire extending from an electrical device, compressing said spring, and securing a terminal onto said wire whereby said spring is held in a compressed condition on said wire, said apparatus comprising:

a terminal applicator adapted to secure a terminal to a wire, electrical-device-supporting means spaced from said terminal applicator,

threading rod means having a free end, wire-holding means on said free end of said threading rod means, said threading rod means being reciprocable along a predetermined path extending from a first position adjacent to said electrical-device-supporting means to a second position adjacent to said terminal applicator, abutment means on said path, said threading rod being movable relatively through said abutment means and said spring, said abutment means being effective to support the one end of said spring which is adjacent to said terminal applicator, and

means for compressing said spring against said abutment means whereby

upon positioning said wire in said wire holding means when said threading rod means is in said first position, movement of said threading rod relatively through said spring to said second position, compression of said spring against said abutment means, and actuation of said terminal applicator, said wire is threaded through said spring, said spring is compressed, and a terminal is secured to said wire and holds said spring in a compressed condition.

3. Apparatus as set forth in claim 2 including means for moving said electrical-device-supporting means towards said terminal applicator concomitantly with movement of said threading rod from said first position to said second position.

4. Apparatus as set forth in claim 3 including spring-supporting means for supporting said spring on said path, said spring supporting means being between said abutment means and said electrical-device-supporting means.

5. Apparatus as set forth in claim 4 wherein said spring-supporting means comprises said threading rod, said spring being telescopically movable onto said rod.

6. Apparatus as set forth in claim 4 wherein said spring-supporting means comprises means adjacent to said free end of said rod when said rod is in said first position.

7. Apparatus as set forth in claim 6 wherein said electrical-device-supporting means supports said electrical device with said wire extending transversely of said path, said threading rod being engageable with said wire during movement towards said terminal applicator.

8. Apparatus as set forth in claim 5 wherein said electrical-device-supporting means is located adjacent to said free end of said threading rod where said rod is in said first position but offset from said path, said electrical-device-supporting means being laterally movable towards said path during movement towards said terminal applicator.
